(57) **CLAIM**

The ornamental design for a headset, as shown and described.

DESCRIPTION

FIG. 1 is a front, left, top side perspective view of a headset showing the new design;

FIG. 2 is a front, right, top side perspective view of FIG. 1; FIG. 3 is a rear, right, bottom side perspective view of FIG. 1;

FIG. 4 is a front elevational view of FIG. 1;

FIG. 5 is a rear elevational view of FIG. 1;

FIG. 6 is a left side elevational view of FIG. 1;

FIG. 7 is a right side elevational view of FIG. 1;

FIG. 8 is a top plan view of FIG. 1; and,

FIG. 9 is a bottom plan view of FIG. 1.

The broken lines in the drawings are directed to portions of the depicted headset that form no part of the claimed design.

1 Claim, 9 Drawing Sheets
